UNDER PICK MOTION FOR LOOMS

Rudolf Hrdina, Tyniste nad Orlici, Bohemia,
CzechoslovakiaApplication July 29, 1946, Serial No. 687,027
In Czechoslovakia April 29, 1946

3 Claims. (Cl. 139—148)

1

All the hitherto known mechanical pick motion systems in looms are consisting of a plurality of members having the object of transmitting the energy from the rotating crank-shaft on the shuttle driving member. The condition of attaining a very quick motion of the shuttle driving member which furthermore is oscillating together with the slay, results in the necessity of using more intricate bulky mechanisms which must be sized, on the one hand, in accordance with the considerable forces resulting from the transmission ratio and, on the other hand, in view of the contradictory consideration of the increase of the inertia forces of the masses moving at high speed. Thus it is necessary to take into account an early wear and tear of the elements manufactured from the familiar materials, which again results in frequent repairs and resetting operations on the pick motion mechanism. A further drawback of the hitherto known designs of under pick motions is the excessive space they require so that they represent an essential obstacle e. g. for the preferable arrangement of dobbies which drawback is further combined with the lack of access to certain parts which is troublesome in the case of incidental repairs or the like, especially on looms already set for operation.

All the above mentioned drawbacks are eliminated in the arrangement of the under pick motion according to the present invention which moreover permits of setting the picker on the loom running.

The invention consists in that the driving energy is admitted to the picking stick through a picking shaft, this latter being provided in the lower third of the slay height above the floor and preferably passing directly through the axis of the oscillating slay of the loom.

The picking shaft is provided with a cam and driven rotatably or pivotally through a transmission deriving from the main driving shaft of the loom, said cam being provided with an adjustable nose which on the performance of the picking motion is resting against one or more adjustable rollers.

For guiding the picking stick preferably a double-joint suspension is used, said suspension being together with said driving cam enclosed in a common casing.

The accompanying drawing illustrates diagrammatically, merely by way of example, one embodiment of the object of the present invention.

2

Fig. 1 showing a section through the axis of the slay and under pick motion mechanism;

Fig. 2 a side elevational view of this under pick motion mechanism the casing cover being removed;

Figs. 3 and 4 showing an elevational respectively plan view of the picking bowl with adjustable nose.

Referring now to the figures, the sidewall 1 of the loom frame carries within the bearing 2 the pivotally arranged casing 3 the hollow pin 9 of which is keyed into the root of the slay 4. The picking stick 7 driving the shuttle is attached by means of a pivot 5 to a rocking lever 6 supported by a pivot 8 within the casing 3, and it is mounted so as to slide on the guide block 11 of the slotted link 10. Said block 11 is pivotally supported in the bearings of the casing 3 through a pivot 12. Said slotted link 10 is provided at the bottom with a pivot 13 and a conical picking bowl 14 being in engagement with the driving cam 15. The eccentric surface of this cam consists of two portions, viz. of the prevalently conical surface 16 provided directly on the cam body and of the nose 17 attached thereto pivotally through a pivot 18. It is obvious that each time the bowl 14 meets the forwardly projecting nose 17 this motion results in a violent rocking of the stick 7 and thus causes "picking."

At the remote side of the cam 15 a supporting roller 20 is arranged on an eccentric pivot 19 within a lug of the casing 3, the picking nose 17 running with its rear surface unto this roller 20 when the picking occurs. By manually angular displacing said pivot 19 the picking nose 17 may be more or less advanced to a forward position thus adjusting the "height" of the tooth and thereby the force of the picking motion of the picking stick 7. The cam 15 keyed on the picking shaft 21 is driven by means of a chain drive 22 deriving motion from the main driving shaft (crankshaft) of the loom, the ratio of the pinions being 1 to 2.

The casing 3 is intended to support all the pick motion members subjected to the greatest strain and which thus may run in an oil bath. In such case it is preferable to provide the top aperture of the casing for the picking stick 7 with the leather bellows to prevent detrimental dust entering the casing. Thereby the life of the pick motion elements is substantially prolonged and furthermore greater stresses are permitted which further allows of a compact design of the under pick motion mechanism preferable especially in the cases of heavy-duty automatic

looms. Instead of a chain drive, gears and/or a rocking link may be used for the drive of the picking shaft 21.

It is further obvious that any other convenient suspension arrangement for the picking stick 1 may be used and other constructional details of said under pick motion may be widely modified without departing from the scope and spirit of the present invention.

I claim:

1. In an under pick motion for looms, the combination with an oscillating slay, of a rotating picking shaft extending through the axis of oscillation of said slay, a casing rotatably mounted on said picking shaft and keyed to said oscillating slay, a picking stick having a picking bowl thereon, means for suspending said picking stick in said casing, a cam fixedly mounted on one end of said picking shaft which extends into said casing, said cam engaging said picking bowl, an adjustable nose on said cam, means adapted to manually adjust said nose during the operation of the loom, and means for driving said picking shaft from the main shaft of the loom.

2. In an under pick motion for looms, the combination with an oscillating slay, of a rotating picking shaft extending through the axis of oscillation of said slay, a casing rotatably mounted on said picking shaft and keyed to said oscillating slay, a picking stick having a picking bowl thereon, means for suspending said picking stick in said casing, a cam fixedly mounted on one end of said picking shaft which extends into said casing, said cam engaging said picking bowl, an adjustable picking nose on said cam, an eccentric roller rotatably adjustably mounted in said casing and adapted to engage the rear face of said picking nose and adjust the same during the rotation of said cam, manually operable means accessible from the exterior of said casing for

adjusting said eccentric roller while the loom is in operation, and means for driving said picking shaft from the main shaft of the loom.

3. In an under pick motion for looms, the combination with an oscillating slay, of a rotating picking shaft extending through the axis of oscillation of said slay, a casing rotatably mounted on said picking shaft and keyed to said oscillating slay, a picking stick having a picking bowl thereon, a slotted link within said casing and suspended therein by means of a rocking lever, said slotted link being slidable on a guide block pivotally supported in said casing by a transverse bearing pin, said picking stick and said picking bowl being attached to said slotted link, a cam fixedly mounted on one end of said picking shaft which extends into said casing, said cam engaging said picking bowl, and means for driving said picking shaft from the main shaft of the loom.
